UNITED STATES PATENT OFFICE

HAROLD H. SIMMS, OF WASHINGTON, DISTRICT OF COLUMBIA, ASSIGNOR OF ONE-HALF
TO EDWIN S. CLARKSON, OF WASHINGTON, DISTRICT OF COLUMBIA.

TYPE-WRITING MACHINE.

1,002,606.

Specification of Letters Patent.

Patented Sept. 5, 1911.

Application filed March 11, 1903. Serial No. 147,256.

To all whom it may concern:

Be it known that I, HAROLD H. SIMMS, a citizen of the United States, residing at Washington, in the District of Columbia, have invented certain new and useful Improvements in Type-Writing Machines, of which the following is a specification.

This invention relates to typewriting machines.

10 It has for its object to provide a typewriting machine in which the keyboard and the type basket or printing mechanism are relatively movable to produce a letter-spacing, and the keyboard and the type basket or printing mechanism and the platen are relatively movable to produce a line-spacing.

15 Other objects and advantages will appear from the following description and will be more particularly pointed out in the appended claims.

20 In the drawings forming a part of this specification: Figure 1 is a perspective view of an embodiment of my invention. Fig. 2 is a vertical section of the embodiment 25 shown in Fig. 1, excepting that all of the connections between the keys and the type-heads are not shown, Fig. 3 is a horizontal section on the line 3—3, Fig. 2, looking in the direction of the arrow, showing some 30 but not all the type-bar levers, Fig. 4 is a detail perspective view of the connections between the type-head and the key, and Fig. 5 is a detail sectional view of another embodiment of the connection between the type- 35 head and the key.

Like numerals indicate like parts throughout all the figures of the drawings and in the specification.

40 While I have shown a machine of the "book type" I wish it to be understood that with changes the same may be adapted to other classes of machines.

45 In the machine shown, a flat platen 1, which is mounted in any suitable manner, is employed. Upon said platen rest tracks 2, and traveling lengthwise of the book on the tracks is a keyboard frame 3.

50 The keyboard frame 3 is advanced by any suitable line-spacing mechanism (not shown) and comprises a housing 4 carrying the keyboard 5, and depending front and back supporting members 6, which carry thereon, at the lower part, pinions 7 for engagement with rack-teeth 8, formed in the 55 tracks 2. Shiftable between the front and

back supporting members 6 is the type basket 9, each type-head 10 thereof having a flexible connection with one of the keys, of the keyboard. The type-basket 9 is advanced upon tracks 12 after each key has been struck to obtain the letter-spacing.

The type-basket is in the form of a segment open toward the operator or the front of the machine and consists of the segment ring 13 suspended from the housing 14 by 6 arms 15. Each type arm 16 has fixed thereto a head 10 having type 17 thereon at an angle to one another. The type arm 16 is pivoted to the segment ring and has an extension 18 which connects to one end of a 7 link 19, the other end of the link being connected to one end of a lever 20 fulcrumed at 21, within the housing 14. The lever 20 carries at its other end a rack bar 23 with which meshes a pinion 24 secured at 25 to 7 the top of the housing 14. Connected to the pinion 24 is the flexible shaft 11 journaled at 27 in the housing 14, and at 28 in the housing 4, which carries the keyboard.

8 The keys depend into the housing 4 and are each connected therein to an arm 29, which is fixed to a rack-shaft 30 journaled in a stud 31 and connected to the flexible shaft 11.

9 When the key is depressed the flexible shaft is rotated through the rock shaft 30, rotating the pinion 24 and forcing the rack bar 23 downwardly, the lever 20 being thereby moved to pull upon the extension 18 of the type-bar through the medium of 90 the link 19 and the type is thrown against the printing surface. The type bar is returned by the spring 32 while the key is returned by the spring 33.

95 When the type-bar lever 20 is raised, adjacent its end which connects to the link 19, it moves a universal segment 34 connected by means of bell-cranks 35 and a link 36 with a spacing dog 37 of ordinary construction, carried by the type-basket to which it is connected by an arm 38, and engaging with rack teeth 37^b on the track 12. Upon the universal segment 34 being moved the spacing-dog 37 is moved in one direction to throw the portion 37^a of the dog into engagement with the rack-teeth 37^b, as in the ordinary spacing dog, and when the universal segment 34 is released, the spring 39 throws the portion 37^a out of engagement with the rack teeth 37^b and the main portion of the 10 11

dog into engagement and the type-basket is advanced, as in the usual manner, by a spring-drawn tape (not shown). To obtain the "upper case" or capital letters which are the upper type on the type-head the type-basket is lifted or moved upwardly. This is accomplished by raising the tracks 12 upon which the type-basket travels. The two racks are connected at each end by inverted U-shaped bars 40 and the inverted U-shaped bars are connected by a horizontal bar 41, which extends through the housing 4. Within the housing is pivoted a lever 42 (see Fig. 2) which is connected at one end to the horizontal bar 41 and at its other end to a key 43 provided with a projection 44. Upon depressing the key 43 and engaging the projection 44 with the inside of the top wall of the housing 4 the tracks will be elevated and consequently the upper case attained.

In the embodiment shown in Fig. 5 the link 19 instead of being connected to the lever 20 is provided with a plunger head 45 which works in a cylinder 46 carried by the type-basket and connected by a flexible pipe 47 to the cylinder 48, carried by the keyboard frame 3 and of larger diameter than the cylinder 46. In the cylinder 48 is mounted a plunger-head 49 which carries the key 5^a. Upon depressing the key arm, air is forced from the cylinder 48 to the under side of the plunger head 45, thereby throwing the type head against the printing surface. A spring 50 returns the plunger head 49 to its original position while a spring 51 returns the plunger head 45 to its original position.

It will be seen that I have produced a book typewriting machine in which the objectionable traveling of the keyboard after the striking of each key is obviated.

It will further be seen that the keyboard and printing mechanism or type-basket are carried by a common frame.

I desire it to be understood that I do not wish to be limited to the details of construction herein shown, and described, and that I may make any changes within the scope of the appended claims.

I am aware that it is old to have a keyboard which is fixed relatively to the platen, and a type-basket which is movable relatively to both the platen and the keyboard, but these constructions either necessitate the entire disconnection of the keyboard from the type basket, thus disassembling the machine, inasmuch as the keyboard and type-basket are not carried by a single frame; or the construction is so complicated that it is not capable of being put to practical use. In my invention both the type-basket and keyboard are carried by a single supporting frame, which makes the handling of the machine much easier, and enables me

to move the machine from place to place without disassembling the parts. The movement of the supporting frame to obtain a line spacing is not a disadvantage, as it is well known that all successful typewriting machines move some part of the machine to produce line spacing. Furthermore, in one of the types with which I am familiar the stationary keyboard is in front of the book, making it inconvenient for the operator to reach the book to make erasures, etc.

Having thus described the invention, the following is what I claim as new therein:

1. In a typewriting machine, the combination with the platen, and the key-board, which are relatively movable in a direction of line spacing, of the type heads movable relatively to the key-board and to the platen in the direction of letter-spacing.

2. In a typewriting machine, the combination with the platen, of the type-heads and the key-board relatively movable in the direction of letter-spacing, and both relatively movable to the platen to produce line-spacing.

3. In a typewriting machine, the combination with the platen, of a key-board adapted for travel along the same in one direction, and the type heads movable with the keyboard in one direction and also movable relatively thereto in a plane parallel with the platen.

4. In a typewriting machine, the combination with the platen, of the keyboard adapted for travel along the platen in one direction, and type heads movable with the keyboard in the same direction and also movable relatively thereto transversely in a plane parallel with the platen.

5. In a book typewriting machine, the combination with the tracks or supports, of the writing mechanism and the keyboard supported on the tracks or supports, said writing mechanism and keyboard being relatively movable in the direction of the line of writing.

6. In a book typewriting machine, the combination with the platen and the tracks or supports, of the writing mechanism and the keyboard supported on the tracks or supports, said writing mechanism and keyboard being relatively movable in the direction of the line of writing.

7. In a book typewriting machine, the combination with the tracks or supports, of the type basket, and the keyboard supported on the tracks or supports, said type basket and keyboard being relatively movable in the direction of the line of writing.

8. In a book typewriting machine, the combination with the tracks or supports, of the writing mechanism and the keyboard supported on the tracks or supports; said writing mechanism being movable in the direction of line spacing and movable rela-

- tively to the keyboard in the direction of letter spacing.
9. In a book typewriting machine, the combination with the tracks or supports, of the writing mechanism and a keyboard carried by the tracks or supports, and movable relatively in the direction of the line of writing, and a flexible connection between the writing mechanism and the keyboard.
10. In a book typewriting machine, the combination with the tracks or supports, of the writing mechanism and the keyboard carried by the tracks or supports and movable relatively in the direction of the line of writing, and a rotatable flexible connection between the writing mechanism and the keyboard.
11. In a typewriting machine, the combination with the keyboard movable in one direction, of typeheads movable relatively thereto in a plane parallel to the printing surface, and rotatable flexible shafts connecting the keys to the type heads.
12. In a typewriting machine, the combination with the key board movable only in the direction of line spacing, of the printing mechanism movable in direction of letter spacing and also in the direction of line spacing.
13. In a typewriting machine, the combination with the platen tracks, of a keyboard mounted thereon to travel only in the direction of line-spacing and a type basket also mounted on the platen tracks to travel in the direction of printing and line-spacing.
14. In a book typewriter, the combination with a single supporting frame, of a type basket mounted on and relatively movable to the frame in the direction of letter spacing, and a keyboard also mounted on said frame movable only in the direction of line spacing.
15. The combination of a platen, a keyboard adapted for travel in one direction over the platen, and a printing mechanism adapted to travel in the direction in which the keyboard travels, carried with the keyboard and adapted to travel independently thereof, in a plane parallel with the printing surface.
16. In a typewriting machine, the combination with a platen, and a keyboard movable transversely of the printing line of the machine, of a printing mechanism movable independently of the keyboard in a plane parallel with the printing surface.
17. The combination with the keyboard frame movable in a path parallel with the printing surface, of a type basket carried thereby and movable in a path parallel with the printing surface transversely to the path of movement of the frame.
18. In a book typewriter, the combination with a type basket movable transversely of a and in the direction of letter-spacing, of a keyboard movable only transversely of the direction of letter spacing.
19. A book typewriter comprising a common frame movable in a plane parallel with the printing surface, a type basket movable transversely of the frame in the direction of letter spacing, and a keyboard held in a fixed relation to the frame.
20. In a book typewriter, the combination with a common frame movable in a plane parallel with the printing surface, a keyboard carried by and being stationary relatively to said frame, and printing mechanism carried by and movable relatively to the frame.
21. In a book typewriter, the combination with a frame, a keyboard movable transversely of the printing line and a type basket movable independently of the keyboard along the printing line.
22. A book typewriter comprising a keyboard movable transversely of the direction of line of printing, a type basket movable in the direction of the line of printing independently of the keyboard, and a common frame carrying said board and basket.
23. In a typewriting machine, the combination with the key and the type head movable relatively in the direction of letter spacing and together in the direction of line spacing, and a rotatable flexible shaft connecting the type head and the key.
24. In a book typewriter, the combination with the keyboard frame movable in the direction of line spacing and carrying a keyboard, of tracks on the keyboard frame, and a type basket traveling on said tracks, relatively to the keyboard.
25. In a book typewriter, the combination with the platen and the keyboard frame carrying a keyboard movable in a plane parallel with the printing surface, of tracks on the keyboard frame, a type basket traveling on said tracks, relatively to the keyboard, and flexible connections between the keyboard and type basket.
26. The combination with the flat platen, the keyboard, a type basket having type heads on which the type are at an angle to one another, revolvable flexible shafts connecting the type basket and the keyboard, and means for moving the basket independently of the keyboard to and from the platen.
27. In a book typewriter, the combination with a flat platen, and a frame movable relatively in the direction of line spacing, of a keyboard carried by the frame and held in a fixed relation thereto, a printing mechanism movable relatively to the keyboard and also carried by the frame, and flexible connections between the keyboard and the printing mechanism, substantially as described.
28. In a book typewriter, the combination with the platen and supports adapted to rest

upon the platen, of a key board supported on the supports, a writing mechanism movable relatively to the keyboard in the direction of letter spacing and embodying 5 type bars, and flexible connections between the type bars and the keys of the keyboard.

29. The combination with the platen and the keyboard, of the printing mechanism supported above the platen, movable relatively to the keyboard in the direction of letter spacing and embodying downwardly 10 striking pivoted type bars each having type

arranged thereon at an angle to one another and each having a flexible connection with its associate key and means causing any the various type on each type bar to strike the printing surface.

In testimony whereof I affix my signature in presence of two witnesses.

HAROLD H. SIMMS.
